DOMESTIC WASHING MACHINE CONSTRUCTION

Simon E. Schroeder, Ripon, Wis., assignor to Barlow & Seelig Manufacturing Company, Ripon, Wis., a corporation of Delaware

Application December 31, 1940, Serial No. 372,547

5 Claims.

(Cl. 68—133)

This invention relates to improvements in the construction of domestic type washing machines.

An object of the invention is to provide an improved washing machine structure in which the chassis includes novel means for dampening and avoiding transmission of vibration from the moving parts to the stationary, supporting structure of the chassis or to the tub.

Another object of the invention is to provide in a washing machine of this kind an improved supporting or chassis structure which includes a tub-enclosing skirt having therein a supporting framework for the tub and driving mechanism formed of simple and easily assembled members connected through vibration dampening means to the chassis structure in such relation to the supporting legs as to effect an even, well balanced distribution of weight.

A further object of the invention is to provide an improved washing machine construction wherein all of the major parts of the chassis are adapted to be fashioned simply and economically from sheet metal.

Other objects and advantages will become apparent in the following description and from the accompanying drawings in which:

Figure 1 is a fragmentary side elevational view of a domestic washing machine embodying the features of the invention, with parts broken away and in section to disclose details of construction.

Fig. 2 is an enlarged fragmentary sectional detail view taken substantially along line 2—2 of Fig. 1.

Fig. 3 is a horizontal sectional view through the machine taken substantially along line 3—3 of Fig. 1, and showing the cross framework of the chassis in plan.

Fig. 4 is an enlarged fragmentary detail sectional view taken substantially along line 4—4 of Fig. 3.

For illustrative purposes the drawings show a domestic washing machine of the double wall type including a round bottom tub 10 mounted within an enclosing chassis 11. Generally described, the chassis 11 includes an annular wall or skirt 12 supported by four equidistant, hollow legs 13 secured thereto which extend well up along the skirt. The tub 10 may be held in place on the chassis 11 by the engagement of an outwardly turned rim flange 14 thereon over the upper edge of the skirt 12, and by supporting its bottom wall upon a central base casting 15 which is carried by a framework or spider structure 16 having its arms attached to the skirt. An agitator 17 is mounted within the tub 10 upon a shaft 18 projecting centrally through the tub and the base casting 15. The means for driving the agitator is supported by the spider 16 and comprises a motor 19 connected by a driving belt and pulley arrangement 20 with the drive shaft of a power

transmission mechanism contained within a housing 21. Manually operable control means 22 may be provided for actuating an agitator clutch (not shown). A drain 23 may communicate with the tub 10 through the base casting 15.

According to the present invention, the spider 16 may be constructed from suitable gauge sheet steel by simple shaping or die stamping operations whereby to attain a high degree of strength with a minimum weight. To this end, the spider 16 is in the form of a pair of crossed, generally channel shaped, flanged members 24 and 25 assembled in back to back relation and having the end portions or arms thereof arranged to be supported by the skirt 12 preferably in line with the legs 13. One spider member, herein the member 24, carries the transmission housing 21 which is secured to the underside of one arm. The other spider member 25 has the motor 19 suspended from one of its arms.

The transmission-carrying arm of the spider member 24 is of a length to extend through a preferably full vertical opening 27 in the skirt 12 and into one of the legs 13 which connects the skirt at the opposite sides of the opening and closes the opening. This leg houses a wringer drive shaft 28 and the connection thereof with the transmission. The transmission-carrying arm or end of the spider member 24 is relatively wide and is secured by means of spaced bolts 29 to the under side of the inwardly projecting flange of an angular bracket 30 which is fixed to the skirt 12 across the opening 27 (Figs. 1 and 2). The opposite end of the spider member 24 as well as both ends of the spider member 25 are preferably of reduced width and are carried upon and secured by bolts 31 to brackets 32 of channel shape. These brackets 32 are mounted in apertures 33 in the skirt 12 (Figs. 3 and 4), and project partially inwardly under the ends of the spider members and partially into the adjacent legs 13 which conceal them from view. These brackets 32 are secured in place by so proportioning the apertures 33 that the upper edges defining the same will seat in notches 34 (Fig. 1) in the side flanges of the brackets, and by securing the side flanges to wings 35 extending inwardly at each side of each aperture.

As may be seen in Fig. 3, the longitudinal dimensions of the spider members 24 and 25 are so proportioned relative to the internal diameter of the skirt 12 that the members may easily and quickly be assembled in the chassis. Stated another way, the spider member 25 is no longer than the internal diameter of the skirt and the spider member 24 only exceeds this dimension in the length of the transmission-carrying arm portion thereof. Since, the spider members lie on diametrical lines within the skirt they intersect directly under and equally support the base casting

15 and the tub. Through this arrangement, moreover, a well balanced relationship is attained in the chassis, and the various parts of the load carried by the spider 16 are substantially evenly divided between the crossed spider members to distribute the entire load uniformly to the four legs of the chassis.

A feature of the invention resides in the improved manner in which both the tub 10 and the skirt 12 are insulated against operation induced vibrations. Since the spider 16 carries the main operating parts, it is the source of practically all vibration; and to prevent transmission of such vibration to the tub a resilient vibration dampener such as rubber disks or gaskets 39 may be interposed between the bottom of the tub 10 and the top of the base casting 15 (Fig. 1). In addition a resilient member such as a rubber gasket 40 may be interposed between the rim flange 14 of the tub and the top edge of the skirt 12.

However, the points at which vibration is most likely to be transmitted is at the connections between the ends of the spider members 24 and 25 and the skirt 12. Accordingly, resilient vibration dampeners such as rubber pads 41 are interposed between the ends of the spider members and the respective supporting brackets 30 and 32. The rubber pads 41 in each instance lie upon the brackets, and those upon the bracket 30 are backed by compression plates or washer disks 42 on which the hanger bolts 29 bear. Those pads 41 which are carried by the brackets 32 are directly engaged and maintained under compression by the ends of the spider members resting thereon. Additional anti-vibration pads 43 lie between the lower faces of the brackets 30 and 32 and compression disks 44 which are held in place by the respective attachment bolts.

From the foregoing it will be apparent that the present invention provides a domestic washing machine structure which is simple in construction and easy to assemble, and which attains, through the use of a sheet metal supporting spider on which all of the machine driving elements are assembled as a unit, a substantial reduction in weight without sacrifice in strength. The improved chassis arrangement, and in particular the crossed frame or spider structure provides for substantially uniform distribution of weight throughout the chassis. In addition the improved vibration dampening means between the tub, the spider and the skirt of the chassis eliminates noise and rattling or jarring from vibration created by the driving means carried upon the spider.

I claim as my invention:

1. In combination in a washing machine of the character described, including a tub, a skirt surrounding said tub and having equally spaced hollow legs in support thereof extending substantially up its outer face, a framework under said tub comprising crossed elongated members having the ends thereof aligned with said legs, and brackets for supporting the ends of said frame members projecting from within said legs through said skirt into overlapping relation to said ends.

2. In a domestic washing machine of the type embodying a stationary tub, an agitator in said tub, means for actuating said agitator including a transmission mechanism, the combination of a skirt surrounding said tub, a plurality of hollow

legs supporting said skirt and extending up the outer face thereof, one of said legs being adapted to house a wringer drive shaft therein, a spider structure at least partially supporting said tub and comprising a plurality of members extending toward said skirt in alignment with said legs, said skirt having an opening in register with said one leg, one of said members being adapted to support said transmission and extending through said opening to permit connection of said wringer shaft with the transmission, a bracket on said skirt across said opening for supporting the transmission-carrying arm of the spider, and brackets concealed within the remaining legs and extending through said skirt for supporting the remaining arms of said spider.

3. In combination in a washing machine of the character described, including a tub, a skirt surrounding said tub and having spaced hollow legs in support thereof extending substantially up its outer face, a framework under said tub comprising crossed, elongated members having the ends thereof aligned with said legs, brackets for supporting the ends of said frame members projecting from within said legs through said skirt into underlying relation with said ends, vibration dampening means interposed between said brackets and said ends, securing bolts extending through said brackets and said ends, and vibration dampening means interposed between the under sides of said brackets and the lower ends of said securing bolts.

4. In combination in a washing machine of the character described, including a tub, a skirt surrounding said tub, a plurality of hollow legs supporting said skirt and extending up the outer face thereof, one of said legs being adapted to house a wringer drive shaft therein, a framework under said tub comprising a plurality of members extending toward said skirt in alignment with said legs, said skirt having an opening in register with said one leg, one of said members being adapted to support a transmission and extending through said opening to permit connection of said wringer shaft with said transmission, a bracket on said skirt across said opening for supporting the transmission carrying member of said framework, a tension bolt extending through said bracket and said one member, vibration dampening means interposed between said bracket and said one member, vibration dampening means interposed between said bracket and the upper end of said bolt, and means housed by the others of said legs extending through said skirt into supporting engagement with the portions of said members aligned therewith.

5. In combination in a washing machine of the character described, including a tub, a skirt surrounding said tub and having four spaced hollow legs in support thereof extending substantially up its outer face, a framework under said tub comprising a pair of crossed elongated members having the ends thereof aligned with said legs, three of said ends stopping short of said skirt, brackets projecting from within said legs through said skirt into overlapping relation with said ends and supporting the ends of said frame member, and an opening formed in said skirt for the reception of the fourth end during assembly.
